UNITED STATES PATENT OFFICE.

EARNEST KRAUSE, OF EL PASO, TEXAS.

LIFT OR ELEVATOR.

SPECIFICATION forming part of Letters Patent No. 296,582, dated April 8, 1884.

Application filed February 27, 1884. (No model.)

To all whom it may concern:

Be it known that I, EARNEST KRAUSE, a citizen of the United States, and a resident of El Paso, in the county of El Paso and State 5 of Texas, have invented certain new and useful Improvements in Lifts or Elevators; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a side elevation of so much of 15 the operating mechanism of a lifter or elevator as is necessary to illustrate my invention; and Fig. 2 is a cross-section, on an enlarged scale, through shaft H and the sliding sleeve G on line x x in Fig. 1.

Similar letters of reference indicate corresponding parts in both the figures.

My invention has relation to vertical rail-ways, or so-called "lifts" or elevators, and is applicable more especially to elevators used 25 in warehouses and freight-depots for trans-porting merchandise from or to the several stories.

My improvement consists in the construction of the operating mechanism, as hereinaf-30 ter more fully described and claimed, whereby the mechanism may be regulated or ad-justed to run fast or slow, according to the weight of the load to be carried, it being ad-justed to run slow, but with great power, when 35 heavy loads are to be lifted, but to run fast, but with lesser power, when lighter loads are to be lifted.

In the accompanying drawings, a a denote 40 two of the standards of the elevator well or frame, having boxes b b, in which the shaft L is journaled, and boxes c c, in which shaft H is journaled. Fastened at opposite sides of the upper shaft, L, are grooved wheels or pulleys A A, over which the rope is carried that 45 raises the platform on one side and its balance-weight or counterpoise on the other. Up-on shaft L are also fastened the large cog-wheel D and a smaller cog-wheel, E. The lower shaft, H, is constructed with a spline, h, and 50 upon it slides a sleeve, G, which is recessed or grooved to fit over the spline h, so that when shaft H is rotated sleeve G will turn with

it. Upon sleeve G, which is free to slide for-ward and back upon shaft H, is fastened the pinion C, adapted to gear with or intermesh 55 with the large cog-wheel D and a cog-wheel, F, which is adapted to gear or intermesh with cog-wheel E upon shaft L. At one end shaft G is cut to form the worm or spiral G', which meshes with the worm-wheel M, fixed upon a 60 shaft, P, which has its bearings in the box d on one of the frame-pieces a, and box e at the lower end of the hanger R. Upon the outer end of shaft P is fastened the sheave or pul-ley K, around which a rope, N, passes, reach-65 ing down to the ground floor or to the base-ment of the building in which the elevator is located. Upon one end of shaft H is fastened the drum or pulley B, around which the hoist-ing-rope O passes, by means of which the plat-form is hoisted up or down.

From the foregoing description, taken in connection with the drawings, the operation of this mechanism will readily be understood. When the several parts are in their relative 75 position shown in the drawings—i. e., the pinion C meshing with the large cog-wheel D—the platform will move slowly up or down, but will carry a very heavy load, on account of the leverage between pinion C and the large wheel 80 D. If, however, smaller loads are to be lifted, the sheave K is rotated by pulling on the end-less rope N, which rotates shaft P and the worm-wheel M, thereby sliding sleeve G upon shaft H in the direction of the arrow until cog-wheel F gears with cog-wheel E on shaft L, at the same time disengaging the pinion C from cog-wheel D. When the parts are in this po-85 sition, shaft L will be rotated considerably faster, thus raising the load placed upon the 90 platform in much less time, but with a proportionately decreased leverage. If desired, shaft H may be provided with a collar or stop, i, which will stop further motion of the sliding sleeve G when the wheels E and F have been 95 brought into the proper position to gear or intermesh with each other.

Having thus described my invention, I claim and desire to secure by Letters Patent of the United States—

The combination, in the hoisting mechan-ism of a lift or elevator, of shaft L, having the pulleys A A, carrying the ropes or chains to which the platform and its counterpoise are

attached, and the gear-wheels D and E, of different diameters, shaft H, having spline *h*, and pulley B, carrying the hoisting-rope which operates the mechanism, sliding sleeve G, provided with pinion C and cog-wheel F, and having the worm G', shaft P, having worm-wheel M, engaging the worm G', and means for rotating shaft P, the whole constructed and combined to operate substantially as and for the purpose shown and set forth.

In testimony that I claim the foregoing as my own I have hereunto affixed my signature in presence of two witnesses.

EARNEST KRAUSE.
